UNITED STATES PATENT OFFICE.

GUSTAVE M. GOLDSMITH AND CARL P. BARTELS, OF HAMILTON, OHIO, ASSIGNORS TO THE MOSLER SAFE COMPANY, OF HAMILTON, OHIO, A CORPORATION OF NEW YORK.

PRESSURE SYSTEM FOR SAFE OR VAULT DOORS AND THE LIKE.

Application filed September 23, 1921. Serial No. 502,623.

To all whom it may concern:

Be it known that we, GUSTAVE M. GOLDSMITH and CARL P. BARTELS, citizens of the United States, residing at Hamilton, Butler county, Ohio, have invented certain new and useful Improvements in Pressure Systems for Safe or Vault Doors and the like, of which the following is a specification.

This invention relates to pressure systems for safe or vault doors and the like, and in particular, relates to a pressure system adapted to be internally adjusted into operable or inoperable condition for closing or for preventing the closing of the safe or vault door on which the system is mounted. Our invention further relates to a power transmission device adapted to be associated with a pressure system so as to be operable to establish or to disable a driving connection between a driving element, such as the pilot wheel, and a driven element, such as the worm shaft, of the pressure mechanism.

This invention is broadly similar to the invention covered in our application filed on September 23, 1921, Serial No. 502,723 relating to improvements in pressure systems for safe or vault doors and the like.

The pressure system of a vault or safe is a mechanism carried on the outside of the vault or safe door whereby the vault door may be forced into absolutely closed position and thus enable the locking bolts to be operated to lock the vault. The mechanism is adapted to be driven by rotating a hand wheel, commonly called the pilot wheel, this wheel being customarily in permanent driving engagement with a worm shaft which connects through a series of gearing with a plurality of rotatable pressure bars carrying cams adapted to engage with bars or blocks mounted on the door frame. The construction is such that when the pilot wheel is rotated, the pressure bars revolve and the motion of the cams against the bars or blocks produces great pressure and forces the door into absolutely closed position in the door frame or jamb. Any one may operate such a pressure system by merely turning the pilot wheel. Thus, no protection is given to a person within the open vault from being locked inside by an unauthorized person, such as a daylight bank robber. One of the objects of our invention is to provide a pressure system incorporating means, preferably concealed, and operable in a secret

manner, whereby the system may be readily and easily adjusted into operative or into inoperative condition, thereby enabling an authorized person before entering the vault to place the device into inoperative condition and enabling such person to restore the device into operative condition when he desires to do so. A further object of our invention is to provide a device of the character described which is secret and is adapted to be controlled by secret means, such as a combination lock or a key lock, or by the secret movement of a movable member. A further object, includes the mounting of a device of such character on the pressure system so that its presence will not be readily apparent to a casual observer. Other objects will be in part obvious and in part pointed out hereinafter.

One of the advantages obtained by our invention is that the pressure system may be disabled so that an unauthorized person, ignorant of the presence of the anti-locking device, or not supplied with the proper key or combination necessary for its operation, may not work the system to close the door of the vault. By this means an unauthorized person, such as a bank robber, is prevented from locking employees of the bank inside of the vault after an attempted burglary. An authorized person is able to set the device so that the system may be operated to close the vault door or may adjust the device so that the system is inoperative and will prevent the closing of the vault door except by a person having knowledge of the existence of the device and of its operation. The operation of the anti-locking device being controlled by a lock mechanism, the adjustment of the pressure system from inoperative to operative condition may not be accomplished by an unauthorized person, and foils the efforts of such person to close the vault door whereon the system is mounted. Other advantages will become apparent hereinafter.

In accordance with our invention, instead of mounting the pilot wheel of the pressure system in permanent driving engagement with the worm shaft thereof, as has heretofore been customary, we mount the pilot wheel for free revolution on the worm shaft. We provide a power transmission device and a controlling mechanism therefor whereby a driving engagement between the

pilot wheel and the worm shaft may be established or disabled, thus placing the pressure system in operative or inoperative condition. Such a power transmission device 5 may comprise a locking element, such as a key or dog, mounted on the pilot wheel for movement into or out of locking engagement within a suitable key-way or recess in the worm shaft of the system. The locking 10 element is adapted to be moved into or out of engagement with the worm shaft and to be controlled by means of a lock mechanism of the combination or key type carried on the pilot wheel, the bolt of the lock being 15 connected with a movable plate provided with stops which coat with and guide the movement of a movable member or collar carrying the locking key or dog. The stops and the collar carrying the locking dog are 20 so associated with each other that when the stops are moved into one position in response to movement of the locking bolt, such as into unlocked position, the stops hold the dog out of a recess of the worm shaft, and 25 when the stops are in another position, as when the bolt of the locking position is in extended or locking position, the dog may enter a recess in the worm shaft. Preferably means are supplied to continually urge the key or 30 dog to move toward the worm shaft and into a recess therein so that such movement may be accomplished whenever the movement of the stops permit. In place of a combination or key lock we may substitute a 35 knob movable axially against the action of a spring into engagement with a rotatable member comprising an eccentric so that the eccentric may then be rotated by the turning of this knob. The eccentric co-operates with 40 a bolt or plate carrying the stops which govern the movements of the locking dog or key into or out of the recess in the worm shaft. By manipulating the knob into engagement with the eccentric and then turning 45 the knob the dog may be directed to enter or to leave the recess of the worm shaft and accordingly a driving connection may be established or disabled between the worm shaft and the pilot wheel. Thus, by the 50 proper manipulation of a lock mechanism or knob, above described, the pressure system may be placed into operative or into inoperative position, and the pressure system may not be converted from inoperative to 55 operative condition except by moving the bolts of the control mechanism into unlocked or withdrawn position, and such movement of these bolts may not be accomplished except by means of a proper key 60 for the key lock, or the working of the proper combination of the combination lock, or the proper preliminary adjustment of the knob of the control means last described.

In order that a clearer understanding of 65 our invention may be had attention is here-

by directed to the accompanying drawings illustrating certain embodiments of our invention. In the drawings, Fig. 1 is a front plan view, somewhat diagrammatical, of our invention associated with a pressure system of a vault door; Fig. 2 is a view partly in section of a portion of the structure shown in Fig. 1 and is taken on the line 2-2 thereof; Fig. 3 is a rear elevation of the pilot wheel without invention thereon, 70 showing the pilot wheel unlocked from the worm shaft, certain parts being broken away for the sake of clearness; Fig. 4 is a view of certain of the parts shown in Fig. 3 and shows the pilot wheel and worm shaft locked together; Fig. 5 is a fragmentary sectional view taken on the line 5-5 of Fig. 3; Fig. 6 is a view similar to Fig. 3 but includes a key lock control; Fig. 7 is similar to Fig. 2 except that it shows the lock illustrated in Fig. 6; Fig. 8 is similar to Figs. 3 and 6 but shows another form of control for the power transmission mechanism; Fig. 9 is a sectional view similar to that of Figs. 2 and 7 but shows the control mechanism illustrated in Fig. 8, the view being taken on line 9-9 of Fig. 8; Fig. 10 is an enlarged view of a detail of the control mechanism illustrated in Figs. 8 and 9; and Fig. 11 is a sectional view of a detail taken on the line 11-11 of Fig. 10. Similar reference characters designate similar parts throughout the several views of the drawings.

Referring to the drawings, 1 indicates the front wall or door frame of a vault or safe with the vault door 2 hinged thereto by means of hinge mechanism 3. On the outside of the door 2 is mounted a pressure system comprising steel pressure bars 4 mounted for rotation in bearings 5 on the outside of door 2, and having at their outer ends cams 6 adapted to engage with bars or blocks 7 attached to the door frame 1. A series of gearing (not shown) permanently connects pressure bars 4 to a worm shaft 8 which is mounted for rotation on the door 2. Power is transmitted to the pressure mechanism by means of a hand wheel 9, commonly known as the pilot wheel, which is fitted with a plurality of handles 10. Wheel 9 is mounted for free rotation on shaft 8, operable means being supplied whereby the wheel 9 may be locked to or be unlocked from shaft 8 to establish or to disable a driving connection between said wheel and shaft and thereby place the pressure system in operative or in inoperative condition. Obviously many various ways and means may be employed which are operable to establish or to disable a driving connection between the pilot wheel and the worm shaft. In the drawings is illustrated one possible construction for establishing or for disabling a driving connection between the pilot wheel and the 120

worm shaft, and several modifications of controlling means for controlling the operation of said power transmission means.

Referring to the drawings, a plate or collar 11 is slidably mounted on the back of the pilot wheel 9 in a slide or guide 12 machined between two lugs 13-13, and carries a locking key or dog 14 adapted to be moved and locked into or to be moved out of and to become unlocked from suitable key-ways or recesses 15 formed therefor in the worm shaft 8. Collar 11 contains an elliptical perforation 16 through which worm shaft 8 extends, collar 11 being movable radially in respect thereto. Collar 11 and key 14 are continually urged to move so as to bring the key 14 into locking engagement within a recess 15 by means of a coil spring 17 coiled about a guide pin 18 mounted on a part 20 on pilot wheel 9, pin 18 being adapted to be loosely received in a suitable recess 19 in one end of collar 11, and the spring 17 being compressed between this end of collar 11 and the portion 20 on the pilot wheel. The part 25 20 may be suitably secured to the rear of the pilot wheel 9 by means of screws 20'.

To govern the movement of the collar 11, and, accordingly, the movement of the dog or key 14 into or out of a recess 15, we provide a movable shifter plate 21 underlying plate 11, and slidably mounted in the guide 12 provided between the lugs 13. Shifter plate 21 is slotted as at 21', with worm shaft 8 extending through the slot 21', shifter plate 21 being movable radially in respect to this shaft. On shifter plate 21 we provide stops or pins 22, which stops extend through elliptical perforations 23 in plate 11. Slots 23 and the pins 22 are so arranged that movement of the pins 22 causes the movement of the locking dog 14 into or out of a recess 15 in the worm shaft. We provide a mechanism for controlling the movement of the shifter plate 21 together with pins 22 thereon in respect to shaft 8.

In one embodiment of our invention, such as is disclosed in Figs. 1, 2 and 3 of the drawings, we provide a combination lock 23 of a well-known type and connect the outer end of its bolt 25 with shifter plate 21, as at 26, so that by operating the bolt 25 into locked or into unlocked position the shifter plate, together with its pins 22, will be moved relatively to the shaft 8, and the dog 14 will be accordingly unlocked from or be locked within a recess 15 in shaft 8, thus adjusting the pressure system into inoperative or into operative condition. As shown, the combination lock comprises the usual knob 27 and dials 28, and is adapted to operate its bolt bar 25 in the usual manner. Thus, a person familiar with the combination of the lock is able, by moving the bolt bar 25 into extended or locking position, to disengage the dog 14 from a recess 15 and ac-

cordingly disable the operative connection between the pilot wheel 9 and the worm shaft 8, and thus adjust the pressure system into inoperative condition. The pressure system may not be restored into operative condition except by withdrawing the bolt bar 25 into unlocked position, and this may not be accomplished without properly working the combination of the combination lock 23. Thus, an authorized person is able to prevent the pressure system from being operated and the vault door from being closed by an unauthorized person. Preferably, the combination lock is mounted so that its dials and knob are on the outer or exposed face 80 of the pilot wheel.

Instead of the combination lock above described we may substitute a key lock mechanism for controlling the operation of the power transmission device. When a key lock mechanism is employed we preferably mount the same in the manner illustrated in Figs. 6 and 7 of the drawings, with the lock mechanism 30 mounted within the pilot wheel 9 and the key tube 31 with the key-hole 31', exposed on the underneath or concealed face of the pilot wheel 9. The control of the power transmission mechanism is similar to the control accomplished by means of the combination lock 23, the bolt bar 25 of the key lock 30 being similarly connected to the shifter plate 21, as at 26, by means of screw or bolt 32. The movement of the bolt bars 25 of both the combination lock 23 and key lock 30 control similar parts in a similar manner. However, when the key lock is present the bolt bar 25 may only be moved in response to the use of the proper key and, in addition, the presence of the anti-locking device is concealed.

As another means for controlling the movement of shifter plate 21 to cause the locking dog 14 to be moved into or out of a recess 15 we may extend shifter plate 21 outwardly as at 40, and provide in said extension an elliptical perforation 41 adapted to receive a cam or eccentric 42 carried on the end of a pin 43 rotatably mounted on the pilot wheel 9 as at 44. We provide a knob 45 held in position on the pilot wheel 9 by means of split flanges 46 so as to be rotatable on the wheel, said knob being provided with a sleeve-like extension 47 adapted to loosely encircle the outer end of pin 43. We mount knob 45 axially with respect to pin 43 and provide a coil spring 48 seated between the sleeve 47 and the periphery of the pin 43 and compressed between an annular shoulder 49 provided on the inside of the sleeve 47 and an annular shoulder 49' provided on the pin 43 to maintain the knob 45 in outward position in respect to pin 43. On the outer end of pin 43 we provide a slot 50 adapted to receive a pin 51 carried 130

- on the knob 45. The pin 51 is adapted to enter into said slot 50 when knob 45 has been pressed inwardly and is adapted to be out of engagement with said slot when the 5 said knob 45 is in normal position or disposed outwardly of said pin 43. Thus, it will be apparent that when the knob 45 is in its normal position in respect to pin 43 it may be rotated freely without affecting 10 the rotation of the pin 43 or the eccentric 42, but when the knob 45 has been pressed inwardly of the pin 43 so that the pin 51 on the knob is engaged in the recess 50 of the pin 43, the turning of the knob 45 will 15 effect the turning of the pin 43 and the eccentric 42, and will correspondingly move the shifter plate 21 radially of the worm wheel shaft 8. Thus, normally the knob 45 may be rotated freely without affecting the 20 condition of the driving connection between the pilot wheel and the worm shaft, but knob 45 may be manipulated into engagement with the pin 43, and when in this position may be turned to establish or to dis- 25 able a driving connection between the pilot wheel 9 and the worm shaft 8 and accordingly adjust the pressure system into operative or into inoperative condition. Preferably we mount the knob 45 on the under- 30neath or concealed side of the pilot wheel 9 so that the presence of the anti-locking device and of the knob for manipulating the same are concealed and will not be apparent to an unauthorized person.
- If desired the entire locking and controlling mechanisms may be concealed and held in position by means of a substantial cover plate 52 secured to the back of the pilot wheel 9. An ornamental nut 53 may also 35 be secured to the outer end of worm shaft 8.
- From the foregoing description the operation of the power transmission device and the control mechanism therefor will be readily understood.
- As many changes can be made in the above construction and many apparently widely different embodiments of this invention could be made without departing from the scope thereof, it is intended that all 40 matter contained in the above description or shown in the accompanying drawings shall be interpreted as illustrative and not in a limiting sense. It is also to be understood that the language used in the following claims is intended to cover all of the generic and specific features of the invention herein described, and all statements of the scope of the invention which, as a matter of language, might be said to fall there- 45 between.
- What we claim is:—
1. The combination with a safe or vault door, or the like, of a pressure system therefor adjustable into or out of operative condition, said system including a hand wheel, 50 and operable means comprising a lock associated with said system and mounted on the rear side of said hand wheel so as to be concealed from view for controlling the adjustment of said system into and out of operative condition. 70
2. The combination with a safe or vault door, or the like, of a pressure system therefor adjustable into or out of operative condition, said system including a hand wheel, and means, comprising a concealed lock mounted on the rear side of said hand wheel and operable independently of said wheel, for controlling the adjustment of said system into and out of operative condition. 75
3. In a pressure system for a safe or vault doors or the like, the combination with a worm shaft having a recess, and a pilot wheel for driving said shaft, of a collar on said wheel and a dog on said collar, said collar being movable in one direction to carry said dog into said recess on said shaft to establish a driving connection between said wheel and said shaft, and movable in another direction to withdraw said dog from said recess to disable said driving connection between said wheel and said shaft, and means for moving said collar in said directions. 80
4. In a pressure system for safe or vault doors or the like, the combination with a worm shaft having a recess, and a pilot wheel for operating said shaft, of a collar on said wheel and a dog on said collar, said collar being movable in one direction to carry said dog into said recess on said shaft to establish a driving connection between said wheel and shaft and movable in another direction to withdraw said dog from said recess to disable said driving connection between said wheel and said shaft, means for governing the movement of said collar in both said directions, said means comprising a spring urging said collar to move in one direction, and a stop adapted to engage said collar and adapted to be moved to determine the movement of said collar in either direction. 90
5. In a pressure system for safe or vault doors or the like, the combination with a worm shaft having a recess, and a pilot wheel for operating said shaft, of a collar on said wheel and a dog on said collar, said collar being movable in one direction to carry said dog into said recess on said shaft to establish a driving connection between said wheel and shaft and movable in another direction to withdraw said dog from said recess to disable said driving connection between said wheel and said shaft, means for governing the movement of said collar in both said directions, said means comprising a spring urging said collar to move in one direction and a stop adapted to engage said collar and adapted to be moved to determine the movement of said collar in either direction. 100
- 115
- 120
- 125
- 130

tion, and means for controlling the movement of said stop, said means comprising an operable lock mechanism.

6. In a pressure system for safe or vault doors or the like, the combination with a worm shaft having a recess, and a pilot wheel for rotating said shaft, of a collar on said wheel and a dog on said collar, said collar being movable in one direction to carry said dog into said recess on said shaft to establish a driving connection between said wheel and shaft, and movable in another direction to withdraw said dog from said recess to disable said driving connection between said wheel and said shaft, means for governing the movement of said collar in both directions, said means comprising a

spring urging said collar to move in one direction and a plate having a stop adapted to engage said collar and adapted to be moved to determine the movement of said collar in either direction, and means for controlling the movement of said stop, said means comprising an operable lock mechanism having a bolt connected with said plate for simultaneous movement therewith.

This specification signed and witnessed this 20th day of September, 1921.
